UNITED STATES PATENT OFFICE.

SAMUEL M. CURWEN, OF PHILADELPHIA, PENNSYLVANIA, ASSIGNOR TO
JOHN A. BRILL, OF PHILADELPHIA, PENNSYLVANIA.

CAR.

SPECIFICATION forming part of Letters Patent No. 761,626, dated May 31, 1904.

Application filed August 21, 1903. Serial No. 170,258. (No model.)

To all whom it may concern:

Be it known that I, SAMUEL M. CURWEN, a citizen of the United States, and a resident of the city and county of Philadelphia, State of Pennsylvania, have invented certain new and useful Improvements in Cars, of which the following is a specification.

The object of my invention is to construct a car-frame which is adapted to the type 10 known as "semiconvertible" or other form of cars in which the sashes are dropped into side pockets which extend to near the lower edges of the sills and to simplify structures of this class by utilizing commercial forms of 15 iron and wood so as to obtain a maximum strength at a minimum cost. This I accomplish by combining an angle-iron sill with a truss-plank and stanchions in the manner hereinafter set forth.

20 I have devised a car wherein the upper sashes are adapted to be lowered into side pockets, the lower end being below the floor-level. The side posts or stanchions are bolted on the outside of a longitudinal angle-iron sill 25 and to a horizontal truss-plank, which latter bears on the iron sill. Either the sill or the truss-plank may support the flooring. By securing the side posts to the outside of the sill and truss-plank they may be made longer and 30 the grooves therein also longer, whereby the sashes may pass down to a greater depth, which will permit of the use of larger sashes. In order to give a stronger construction between the side posts and side sills, the posts 35 may rest preferably on an outwardly-extending flange formed on the sill, the post then being bolted to the upright web of the sill, as shown in the drawings.

By the construction herein shown and 40 described I am enabled to build a car having part metallic side sills over forms, which materially lessens the cost and time of production.

In divisional applications filed November 24, 1903, bearing Serial Nos. 182,464 and 182,465, 45 respectively, I have claimed specifically the modifications shown in Figures 2 and 4.

Further details of improvement will be hereinafter explained, and further pointed out in the claims.

In the drawings forming part of this specification, Fig. 1 is a cross-section of one side of a car, showing sill-floor, post, truss-plank, &c. Fig. 2 is a similar view of a car in which a Z-iron has been used in the sill construction. Fig. 3 is a similar view of a car in which an angle-iron of two webs is used. Fig. 4 is a perspective view, partly in section. Fig. 5 is a section on the line 5 5 of Fig. 1. Fig. 6 is a section on the line 6 6 of Fig. 4 looking in the direction of the arrows. Fig. 7 is a section on the line 7 7 of Fig. 2 looking in the direction of the arrows and with the sash in its lower position.

In the accompanying drawings, 1 represents the car-flooring; 2, the outside sheeting secured to the post, and 3 the side posts or stanchions, and 4 the side sills of the car, which is made of channel or angle iron. In the construction shown in Fig. 1 the sill is composed of a channel-iron having a vertical 70 web 5 and the upper and lower horizontal flanges 6 and 7. In the construction shown in Fig. 2 the side sill is composed of a beam, substantially Z shape in cross-section, having an upright web 8, the upper horizontal web 75 9, and the lower horizontal web 10. Fig. 3 has a sill composed of an upright web 11 and the horizontal flange 12, while in Fig. 4 the sill consists of the upright web 13 and upper flange 14. The car is not shown in full, as it 80 is understood that both sides are constructed alike, the side sills being secured together in any of the well-known ways.

On the top of the side sill rests the longitudinal truss-plank 15, which, as shown in 85 Figs. 1 and 2, may be bolted to the upper flanges 6 or 9 of the sills by means of bolts 16. The plank is also bolted or screwed to the stanchions by bolts 20^a, 20^b or screws. The upper flange 9 in Fig. 2 is long enough 90 to extend inwardly beyond the truss-plank, so that the flooring may rest thereon, as at 17.

- The side posts 10 are provided with grooves 18 to receive the upper panel 19 when the car is converted. The stanchions are long enough to reach to the bottom of the side sill and the 5 ends adapted to rest on the outwardly-extending lower flange of the sill in the construction shown in Figs. 2 and 3. The post is secured against the upright web 5, 8, 11, or 13 of the sill by means of the bolts 20, which pass 10 transversely through the posts and side sills, a filling-piece 21 being inserted at the end of the post to rest on the sill-flange and make a proper connection for the post and flange, it being held in place by the lower bolt 20.
- 15 A modified form of construction is that shown in Fig. 4, wherein the side sill is composed of an angle-iron beam having the upright web and the inwardly-extending flange, which supports the floor, and truss-beam similar to that shown in Fig. 2. In this form and that shown in Fig. 1 it is necessary to provide a second filling-piece 22 at the lower end of the post to close the end between the outside sheeting and the side sill.
- 20 25 Another way of constructing my invention is shown in Fig. 3, wherein the side sill is composed of a similar angle-beam, as shown in Fig. 4, but so placed that the flange is at the bottom and extending outwardly. In this 30 form the post is secured to the sill the same as in Fig. 2. The only difference in this form from the others is that the car-flooring extends farther and rests on the top edge 23 of the sill and the truss-plank rests on the floor 35 ends.
- Having described my invention, what I claim is—
1. A car having an angle-iron sill, a longitudinal truss-plank bearing on said sill, and 40 stanchions or posts secured to the sill and plank.
  2. A car having an angle-iron side sill, a truss-plank fixed to said sill, stanchions secured thereto, and a car-flooring resting on 45 the side sills, said stanchions extending to the bottom of the side sill.
  3. A car or similar vehicle having angle-iron side sills, truss-planks fixed to said sills, vertically-disposed stanchions secured to the 50 outside of said sills, and extending to the bottom thereof, and a car-flooring resting on the upper part of said sill.
  4. A car or similar vehicle having angle-iron side sills, vertically disposed, longitudinal 55 truss-plank supported on the side sill, a car-floor resting on the side sill, and stanchions secured to the outside of the sill, and passing below the floor-level.
  5. A car or similar vehicle, having side sills 60 composed of angle-iron having an upright web, stanchions secured to the upright web, extending to the bottom thereof, a sash-groove

in the stanchion, a longitudinal truss-plank supported on the side sill and secured to the posts, and a car-floor adapted to rest on the 55 side sill.

6. A car or similar vehicle, having a side sill, composed of an upright web adapted to support a car-floor, a horizontal web extending outwardly, stanchions secured to the vertical web of said sill and resting on the horizontal web and sash-grooves in the stanchions extending to the horizontal sill-web. 70

7. A car or similar vehicle having a side sill composed of a vertical web, an inwardly-extending horizontal web, stanchions secured to the vertical web and extending to the bottom thereof, and a filler secured to the end of the stanchion and to the sill. 75

8. A car or similar vehicle having an angle-iron side sill, composed of a vertical web, and outwardly-extending horizontal flanges, stanchions provided with grooves secured to the vertical web of the sill resting on the horizontal flange, the grooves in said stanchion 85 extending to said horizontal web of the side sill. 80

9. A car or similar vehicle having a side sill comprising an upright web, and an outwardly-extending horizontal flange, car-flooring resting on the upright web, posts, having longitudinal grooves, secured to the upright web, said post and grooves extending below the car-flooring, and a longitudinal filler secured to the lower end of the post and to the sill. 90

10. A car-frame having an angle-iron sill with a truss-plank bolted to the upper edge thereof. 95

11. A car having an angle-iron sill with a truss-plank secured to the upper edge thereof, and stanchions bolted to said sill and truss-plank. 100

12. In a car or similar vehicle, an angle-iron side sill, grooved posts fixed to the outer side of said sill so that sash-pockets will be formed 105 exterior to said sills.

13. In a car or similar vehicle, an angle-metal side sill with grooved posts fixed to the exterior thereof, and a web on the lower edge of said sill on which said posts rest. 110

14. In a car or similar vehicle, an angle-metal side sill with grooved posts bolted to its exterior surface, so that the sash-grooves extend adjacent the lower edge of said sill. 115

15. In a car or similar vehicle, an angle-metal side sill with grooved posts fixed to its exterior and means for limiting the movement of sashes in said grooves adjacent to the lower edge of said sill. 115

16. In a car or similar vehicle, an angle-metal side sill with grooved posts fixed to its exterior, and filling-pieces connected with said posts. 120

17. In a car or similar vehicle, an angle-

- metal side sill with grooved posts fixed thereto, a web on which said posts rest near the lower edge of said sill, and filling-piece fixed to said posts.
- 5 18. In a car or similar vehicle, an angle-metal side sill with a truss-plank bolted thereto.
19. In a car or similar vehicle, an angle-metal side sill with a truss-plank fixed with an edge on said sill by means of bolts.

20. In a car or similar vehicle, an angle-metal side sill with a truss-plank bolted thereto so that each have abutting edges.

Signed in the city and county of Philadelphia, State of Pennsylvania, this 11th day of 15 August, 1903.

SAML. M. CURWEN.
